FOOD VENDING UNIT

Otto E. Werner, Skokie, Ill., assignor to Automatic Canteen Company of America, Chicago, Ill., a corporation of Delaware

Filed June 18, 1962, Ser. No. 70,590

Term of patent 7 years

(Cl. D52—3)

The undisclosed side of the food vending unit is substantially the same in appearance as the side shown and the rear is plain in appearance.

The dominant features of my design reside in the portions shown in full lines.

I claim:

The ornamental design for a food vending unit, as shown and described.
